CENTRIFUGAL DRIER

Anton C. Schmelzer, Cleveland, Ohio

Application September 7, 1935, Serial No. 39,599

7 Claims. (Cl. 210—71)

This invention relates to laundry machines and particularly to centrifugal rinsing and drying apparatus, especially of that type intended for home or domestic use in which a rotary, perforated basket extracts liquid from the materials to be dried and directs the extracted liquid into a tub, from which the liquid is then discharged by means of a suitable pump.

The rotary basket in present day centrifugal driers of the type referred to is ordinarily driven and supported by means which are connected either to the top of the basket or the bottom of the basket or both in order to eliminate obstructions in the basket of the drier. As centrifugal driers of this construction have their basket supported on points substantially spaced from the center of gravity of the basket, a smooth and proper rotation of the basket entirely depends upon proper and equal distribution of the material charged into the basket. It is well known that the ordinary operator of a centrifugal drier often neglects the proper distribution of the material in the basket of the drier and this effects very substantial undesirable vibrations of the drier, which vibrations accelerate wear and tear on the drier and often make the operation of such a drier unsafe.

The present invention has for its principal object to provide a centrifugal drier with supporting means for its rotary basket arranged peripherally in a plane between the top and bottom portion thereof and in proximity of the center of gravity of the basket, so as to decrease the undesired effects of unequal distribution of a charge of the basket.

Another object of the invention is to provide a centrifugal drier with rotary supporting means and means on the side wall of the basket between the top and bottom portion thereof and in proximity of the center of gravity of the basket, for cooperation with the rotary supporting means in suspending the basket within the drier.

A further object of the invention is to provide a centrifugal drier with rotary supporting means and means on the side wall of the basket between the top and bottom portions thereof and in proximity of the center of gravity of the basket for universally suspending the basket in said supporting means and permit of the basket being automatically by gravity action aligned with respect to the axis of rotation of said supporting means in that the center of gravity is brought into alignment with said axis.

With these and incidental objects in view, the

invention consists in certain novel features of construction and combination of parts, the essential elements of which are set forth in the appended claims; and a preferred form of embodiment of the invention is hereinafter shown with respect to the drawings accompanying and forming part of this specification.

This application is a continuation in part of my copending prior application Serial No. 688,513 filed September 7, 1933.

In the drawings Figure 1 is a longitudinal sectional view of a centrifugal drier embodying the improvements according to the invention.

Figure 2 is an enlarged cross sectional view on line 2—2 of Figure 1.

Figure 3 is an enlarged cross sectional view on line 3—3 of Figure 1, and

Figure 4 is a perspective view of one of the arms supporting the ring of the supporting means for the basket.

Referring more particularly to the drawings 1 denotes a centrifugal drier tank or tub in which a clothes basket 25 is rotatably supported, which basket is adapted to be coupled with and driven from the wringer gear box of a wringer type washing machine, not shown, by means of a drive shaft 6. This shaft is enclosed in a tubular housing 7, supported at opposite ends adjacent one side of the drier tank 1 by means of upper and lower brackets 8 and 9, which brackets are secured to and project laterally from the tank 1.

Drier tank 1, preferably cylindrical in shape, is reduced at its lower end to form a drain chamber 10 and a cylindrical portion 11, which portion forms part of a housing of a pump 12. As shown the pump housing consists of two halves, a lower half 13, formed by the inwardly bent and suitably shaped lower part or wall of portion 11, and an upper half 14 consisting of a preferably cup-shaped inset member, which rests upon and is welded to said lower half 13. A plurality of impeller blades 15 rotate in the portion 11 and discharge liquid into the pump housing. These impeller blades are secured to inner and outer spaced, bell-shaped blade retainers 16 and 17 respectively, the lower ends of which communicate with the interior of the pump housing. A downwardly and inwardly inclined drain board 18 is formed with an outer depending annular flange 19, which seats snugly within the portion 11 and rests upon the upturned flange 20 of the upper half 14 of the pump housing. Drain board 18 is also formed with a short inner depending annular flange 21 surrounding the central drip opening 22.

This flange 21 seats over the outer retainer member 17 and directs water extracted from the clothes between the bell-shaped retainers 16 and 17, from whence it is discharged in an obvious manner, when the impeller blades and their retainers are rotated.

Mounted within the tank for rotation about the axis is a short shaft 24, which extends downwardly through the tank and carries a perforated metal clothes basket or extractor 25 in which the clothes to be rinsed and dried are placed. This basket is formed intermediate its ends with an outwardly bulged curved portion 26, which seats within a supporting ring 27 in turn welded or otherwise suitably secured to the upper ends of a plurality of supporting arms 28, substantially U-shaped in cross section, and preferably three in number. The lower portion of ring 27 is curved in inwardly corresponding to the curvature of bulged portion 26 to seat the basket for free universal movement, and the upper portion 29 of the said ring is straight to permit insertion of the basket therein and removal therefrom. A driving pin 30 projects outwardly from the basket 25 through a notch 31 in the straight portion 29 of ring 27, thus locking these parts against independent movement.

Though the curvature of the bulged part 26 of the basket 25 corresponds closely to the curvature of the curved portion of the ring 27, and a snug fit is had between these parts, the fit is such that the basket is free for universal movement. Consequently, should the weight of clothes be unevenly placed in the basket, the latter will automatically tilt in its swivel ring mounting and bring the weight closer to the axial center of the drive shaft, thus eliminating objectionable chattering and strain by keeping the basket in perfect balance.

The lower angularly portions of the arms 28 have arc-shaped ends 28' which fit snugly together in the form of a circle and are clamped to a drive head 32 of the shaft 24 by means of a cap 33, the depending annular flange 34 of which is formed with slots 35 to receive the upstanding flanges 36 of the U-shaped arms. The inner impeller blade retainer 16 is pressed upon or otherwise suitably secured to drive head 32 for rotation therewith. The upper squared end 37 of the shaft 24 fits within the squared opening 38 of the drive head 32 and a bolt 39 passes through the cap 33, arms 28 and into said squared end of the shaft to clamp these parts securely together. The shaft 24 extends downwardly through a bearing support 40, the upper end of which is enclosed by the depending sleeve flange 41 of the drive head 32 on which flange the impeller blade retainer 16 is fixed.

The bearing support 40 is threadedly connected with a bearing housing 42, which supports the lower half 13 of the pump 12, an integral part of the drier tank 1, and thus clamps the drier tank to the bearing support 40. The housing 42 also encloses and supports a thrust bearing 43, seating the lower end of the bearing support 40. A bearing member 44, screwed into the lower end of the housing 42, rests against a packing member 45, which prevents escape of oil. The entire weight of the drier is carried by supporting bracket 8 secured at one end to the bearing sup-

port housing 42 and at its other end to the tubular housing 7, enclosing drive shaft 6.

Having thus described my invention.

What I claim is:

1. In a centrifugal drier a tank having an apertured bottom, a basket embodying a curved ring portion on its side wall centrally thereof arranged within said tank, a driving and supporting shaft for said basket extending through the apertured bottom of said tank thereinto, and supporting means coupled with said shaft and seating the ring portion in the side wall of said basket so as to support said basket in a plane in proximity of the center of gravity of said basket.

2. In a centrifugal drier a tank having an apertured bottom, a basket within said tank, said basket embodying a circumferential, curved seat in the side wall of the basket centrally thereof, a driving and supporting shaft for said basket extending through the apertured bottom of said tank thereinto, and supporting means rigidly coupled with said shaft and universally seating said basket by means of its curved seat.

3. In a centrifugal drier a tank having an apertured bottom, a basket embodying a curved ring portion on its side wall centrally thereof arranged within said tank, a driving and supporting shaft for said basket extending through the apertured bottom of said tank thereinto, and means rigidly coupled with said shaft and universally seating said basket by means of its curved ring portion, said supporting means including a ring-shaped seating member having its lower inner surface shaped to correspond to the outer curvature of the ring portion on the side wall of said basket.

4. In a centrifugal drier a tank having an apertured bottom, a driving and supporting shaft extended into said tank through the apertured bottom thereof, a plurality of uprights secured to the upper end of said shaft, a supporting ring secured to said uprights having its inner surface shaped to form a ball seat, and a basket embodying a curved central portion resting within the ball seat of said ring for universal movement with respect thereto.

5. In a centrifugal drier a tank having an apertured bottom, a driving and supporting shaft extended into said tank through the apertured bottom thereof, a plurality of L-shaped uprights having their horizontal portions secured to the upper end of said shaft, a supporting ring secured to and supported by the vertical portions of said uprights, and a basket carried and encircled by said supporting ring, said ring and basket embodying cooperating curved seating surfaces to permit of universal movement between said ring and said basket.

6. A centrifugal drier as described in claim 5, wherein the seating surface of said ring consists of an upper cylindrically-shaped surface and a lower ball-shaped surface, so as to permit of ready seating and unseating of said basket in said ring.

7. A centrifugal drier as described in claim 5, embodying coupling means between said ring and said basket, said coupling means permitting of free universal movement between said ring and said basket.

ANTON C. SCHMELZER.
